POST AURICULAR PRESSURE DRESSING

James L. Geraci, Cincinnati, Ohio, assignor to Xomox Corporation, Cincinnati, Ohio

Filed Apr. 29, 1974, Ser. No. 465,285

Term of patent 14 years

Int. Cl. D24—04

U.S. Cl. D63—1 J

FIG. 1 is a perspective view of a post auricular pressure dressing, showing my new design;

FIG. 2 is a top plan view thereof;

FIG. 3 is a bottom plan view thereof;

FIG. 4 is an elevational view of the right side of FIG. 1;

FIG. 5 is an elevational view of the right end of FIG. 4;
4; and

FIG. 6 is an elevational view of the left end of FIG. 4.

I claim:

The ornamental design for a post auricular pressure dressing, as shown and described.
